CLAIM

The ornamental design for a hunting stand trailer and lift, as shown and described herein.

DESCRIPTION

FIG. 1 is a top perspective view of a hunting stand trailer and lift in accordance with principles of the present disclosure, and shown in an upright condition with a hunting stand; FIG. 2 is a left side view of the hunting stand trailer and lift of FIG. 1;

FIG. 3 is a right side view of the hunting stand trailer and lift of FIG. 1;

FIG. 4 is a rear end view of the hunting stand trailer and lift of FIG. 1;

FIG. 5 is a front end view of the hunting stand trailer and lift of FIG. 1;

FIG. 6 is a top plan view of the hunting stand trailer and lift of FIG. 1;

FIG. 7 is a bottom plan view of the hunting stand trailer and lift of FIG. 1;

FIG. 8 is a top perspective view of a hunting stand trailer and lift of FIG. 1, and shown in a transport condition with a hunting stand; and,

FIG. 9 is a left side view of the hunting stand trailer and lift of FIG. 8.

The broken lines represent environmental structure that forms no part of the claimed design.
